(57) **CLAIM**

The ornamental design for a storage container for recreational vehicle, as shown and described.

DESCRIPTION

FIG. 1 is a rear, right side isometric view of a storage container for recreational vehicle according to the design; FIG. 2 is a top plan view thereof;

FIG. 3 is a bottom plan view thereof;

FIG. 4 is a rear elevation view thereof;

FIG. 5 is a front elevation view thereof; and,

FIG. 6 is a right side elevation view thereof, the left side being a mirror image thereof.

The broken lines illustrate portions of the storage container for recreational vehicle which form no part of the claimed design.
